UNITED STATES PATENT OFFICE.

EDWARD F. WENTWORTH, OF SINKING SPRING, PENNSYLVANIA, ASSIGNOR TO
MODEL UNDERWEAR COMPANY, OF SINKING SPRING, PENNSYLVANIA, A COR-
PORATION OF PENNSYLVANIA.

UNDERGARMENT.

1,089,888.

Specification of Letters Patent. Patented Mar. 10, 1914.

Application filed October 17, 1913. Serial No. 795,625.

To all whom it may concern:

Be it known that I, EDWARD F. WENTWORTH, a citizen of the United States, residing at Sinking Spring, in the county of 5 Berks and State of Pennsylvania, have invented certain new and useful Improvements in Undergarments, of which the following is a specification.

This invention relates to undergarments 10 particularly adapted for women's wear and commonly known as "union suits".

The principal objects of this invention are, to provide a union suit which affords absolute freedom in walking, and which will 15 not accidentally gap when the wearer assumes a sitting or stooping posture; and to provide a union suit which while readily manipulated, has its parts so correlated as to afford comfort to the wearer.

Other objects of this invention are, to 20 provide such a garment with leg portions formed integral with the body portion; to provide the inner sides of said leg portions with separate seat-forming gussets; and to 25 provide aprons connecting the leg portions and bridging the intervening space to form a skirt.

This invention further includes all of the 30 various novel features of construction and arrangement hereinafter more definitely specified.

In the accompanying drawings, Figure 1 is a front elevational view of a union suit conveniently embodying my invention; Fig. 35 2 is a fragmentary front elevational view of the lower portion of the garment shown in Fig. 1, with the front apron removed; and Fig. 3 is a plan sectional view of the garment shown in Fig. 1 taken through the 40 leg portions, on the line 3—3 in said figure.

In said figures, the garment comprises the body portion 5 having the neck 6 and armlets 7 and 8, and the leg portions 10 and 11 which are connected by inverted V-shaped 45 aprons 12 and 13, the apron 12 having its opposite inclined edges 14 and 15 respectively connected with the front of the leg portions 10 and 11 by stitching 16, and the apron 13 having its opposite inclined edges 50 18 and 19 connected with the back of the said leg portions 10 and 11 by stitching 20. By thus connecting the leg portions 10 and 11, it will be obvious that a continuous skirt

is formed by the alternate webbing, comprising the aprons 12 and 13 and the outer 55 sides of said leg portions 10 and 11 respectively.

The garment is preferably formed of a circular knit tube which may be slit centrally up the front and back to the point 60 indicated at 22, and the front and back webbing connected from the bottom to the point indicated at 23 by stitching 24, to close the tube forming the leg portion 10, and by similar stitching 25 to the point indicated 65 at 27, to close the tube forming the leg portion 11.

The leg portion 10 is provided with seat-forming gussets 30 and 31, one edge of the gusset 30 being connected with the free forward edge of the leg portion 10 by stitching 32, while the corresponding edge of the gusset 31 is similarly connected with the free rearward edge of the leg portion 10, the opposite edges 34 of said gussets being free 70 and open. The lower edges of the gussets 30 and 31 are joined by stitching 35, and said gussets are respectively connected along their upper edges to the front and back free edges of the leg portion 11 by the respective stitchings 36 from the point 22 to the point 37. The leg portion 11, like the leg portion 10, is provided with seat-forming gussets 40 and 41, one edge of the gusset 40 being connected with the free forward edge 80 of the leg portion 11 by stitching 42, while the corresponding edge of the gusset 41 is connected with the free rearward edge of the leg portion 11, the opposite edges 44 being free. The gussets 40 and 41 have their 90 lower edges joined by stitching 45, and their upper edges respectively connected to the front and back edges of the leg portion 10 by the stitching 46 from the point 22 to the point 47.

It will be readily observed that the seat-forming gussets of the respective leg portions normally overlap in telescopic relation, and form a substantially closed garment which does not become accidentally 100 disarranged, but, on the contrary, automatically adjusts itself.

The union suit constructed in accordance with my invention is advantageous, in that it not only provides the upper and lower 105 undergarment, but also provides a skirt

which does not interfere with the tight-fitting gowns, and also provides a desirable shield when worn with the so-called "shadow" gowns.

5 I do not desire to limit this invention to the precise details of construction and arrangement herein set forth, as it is obvious that various modifications may be made therein without departing from the essential features of the invention as defined in the appended claim.

It will be noted that the garment above described is capable of being worn with either side as the front or back. Both the 15 front and back being identical, the garment may be reversed if desired so that all parts will be submitted to an equal amount of wear.

Having thus described my invention, I claim:

An undergarment having a body portion and leg portions, said leg portions being connected by aprons forming a continuous skirt, one of said aprons having its lateral edges stitched to the front of the leg portions, and the other apron having its lateral edges stitched to the back of said leg portions.

In witness whereof, I have hereunto set my hand this 16th day of October, A. D. 30 1913.

EDWARD F. WENTWORTH.
